United States Patent Office

Des. 182,538

Patented Apr. 15, 1958

182,538

AGRICULTURAL VEHICLE

Fred Thomas Smith, Park Forest, Ill., assignor to Precision Research and Development Company, Kansas City, Mo., a corporation of Missouri

Application December 31, 1956, Serial No. 44,369

Term of patent 3½ years

(Cl. D14—3)

Des. 182,538

PAGE 2

Fig. 3.

Fig. 4.

Fig. 1 is a side perspective view of an agricultural vehicle embodying my new design;

Fig. 2 is a perspective view, showing the opposite side and rear;

Fig. 3 is a plan view; and

Fig. 4 is a front elevational view with portions broken away for convenience of illustration.

The essential features of my design reside in those portions shown in full lines.

I claim:

The ornamental design for an agricultural vehicle, as shown and described.
